His Attorney.

UNITED STATES PATENT OFFICE.

HARRY SEMPLE, OF ST. LOUIS, MISSOURI, ASSIGNOR TO THE DIAGRAPH COMPANY,
OF ST. LOUIS, MISSOURI, A CORPORATION OF MISSOURI.

FOUNTAIN-BRUSH.

1,184,662.

Specification of Letters Patent. Patented May 23, 1916.

Application filed December 7, 1914. Serial No. 875,932.

To all whom it may concern:

Be it known that I, HARRY SEMPLE, a citizen of the United States, and residing at St. Louis, in the State of Missouri, have invented certain new and useful Improvements 5 in Fountain-Brushes, of which the following is a specification.

This invention relates to brushes, and more particularly, to fountain brushes, in 10 which the material used is stored in the font or reservoir, and fed to the brush element or tuft.

Some of the objects of this invention are to construct a fountain brush which will accurately and positively feed the contents of 15 the font to the brush, and in which the quantities fed can be regulated and controlled by shaking the brush.

Further objects are to construct a fountain brush in which the operating parts will 20 not clog, which will not leak, which can be carried in the pocket and will not soil either the pocket or the hands, and which is simple in construction and operation, and cheap to 25 manufacture.

Further objects will appear from the detail description taken in connection with the accompanying drawing, in which:

Figure 1 is a side elevation of a fountain 30 brush embodying this invention; Fig. 2 is a longitudinal vertical section; Fig. 3 is a section on the line 3—3, Fig. 2; Fig. 4 is a longitudinal vertical section of a brush, showing another embodiment of this invention; and, Fig. 5 is a section on the line 5—5, Fig. 4.

Referring to the accompanying drawing, 10 designates a hollow handle having one end thereof closed to form a reservoir or 40 font. A socket 11 has a reduced part 12 threaded into the other end of the font, and this socket has a recess 13 therein opening into the font. A brush element sleeve 14, having bristles 15 and a tube 16, is threaded 45 into the socket piece, a washer 17 being interposed to form a good joint.

A valve 18 has a stem 19, passing through 50 the hole in the socket piece forming the valve seat for the valve, and the other end of the stem has riveted thereto a head or piston 20. A light spring 21 encircles the valve stem and bears, at one end, against the head or piston 20, and, at its other end, against the socket piece, so as to normally 55 hold the valve closed. The head or piston is

slightly smaller in diameter than the inside diameter of the font 10, and is recessed or notched at its periphery, as shown at 22, so as to provide a clear space or spaces between the piston and the font. 60

In order to fill the brush, the socket piece, which is knurled and carries the brush element, as well as the valve, is removed from the font, and, after filling, replaced. If the brush is now held with the tuft down and 65 given a rapid downward movement, the valve 18 will be opened against the tension of the light spring 21, so as to permit some of the contents of the font to pass the valve and enter the tuft. This opening of the valve 70 is caused partly by the inertia of the head 20, and partly by the movement and inertia of the liquid in the font. The head 20 is made heavy enough so as to possess considerable 75 inertia, and is, furthermore, spaced laterally from the walls of the font, by making it of smaller diameter than the font, and by providing the recesses 22, which permit the liquid to flow past the head to the valve. As this liquid moves when the brush is shaken, 80 the head 20 will move with it, and the movement of this head will, in turn, open the valve. The more violent the movement, the greater will, of course, be the opening of 85 the valve, and the greater will be the amount of liquid fed to the tuft. 85

In the construction shown in Figs. 4 and 5, the font 30 is, as in Figs. 1, 2 and 3, provided with a socket 31, carrying the valve 32, valve stem 33, head 34, and the light 90 spring 35. These parts are of substantially the same construction as in the other embodiment, and the head 34 is, in this case, also of smaller diameter than the font, and is also provided with recesses 36 in its circumference. The socket piece 31 has screwed thereon a sleeve 37 having attached thereto, or formed thereon, a tube 38, which receives the corrugated sleeve 39 carrying the tuft 40. The tube 38 is flanged over or reduced at its lower end, as shown at 45, so as to engage the tuft. 95

A cap 41, having an enlarged or expanded part 42, slips over the tube 38, so as to close the brush, thereby permitting the brush to be carried in the pocket. The other end of the font 30 is provided with a cap 43 screwed thereon, and having a depression 44 therein to receive the cap 41. When the brush is in use, the cap is placed in the de- 110

pression 44, with the open end out, as shown in Fig. 4, thus preventing any drippings from the brush, which may have accumulated in the cap, being discharged into the depression 44 or over the surface of the rear end of the font.

The general operation of this brush is substantially the same as that of the other embodiment, and a detail description of its 10 operation will, therefore, be unnecessary. The liquid, passing by the valve, enters between the corrugated sleeve 39 and the tube 38, and passes to the tuft, the reduced part 45 insuring a gradual feed. When the brush 15 is not in use, the tuft is covered by the cap 41, this cap being inserted into the end of the brush font when the brush is in use. This construction is especially suitable for 20 small brushes. It will, therefore, be seen that the invention accomplishes its objects. A device is produced which has a minimum of moving parts, and is simple in construction, as well as operation. In order to feed 25 the liquid to the brush element, or tuft, it is only necessary to shake the brush, the amount fed being governed by the extent of the shaking movement. The operator, therefore, need not depress a valve actuating member. Moreover, since the liquid can 30 only be fed to the brush when it is held with the tuft down, there is no liability of failure to feed on account of the liquid being in the upper end of the font, as in those 35 constructions where a button or the like is used to operate the valve. The brush can be readily filled, and can, also, be readily cleaned by simply removing the socket, together with the mechanism attached thereto.

40 It is obvious that various changes may be made in the details of construction with-

out departing from the spirit of this invention, and it is, therefore, to be understood that this invention is not to be limited to the specific construction shown and described.

Having thus described the invention, what is claimed is:

1. A fountain brush comprising a font, a brush element, a valve between said parts, a momentum member within the font, said member being constructed and arranged for operation, by movement of the liquid in the font, to open the valve, and means for normally closing the valve.

2. A fountain brush comprising a font, a brush element, a valve between said parts, a movable head positioned within the font and connected with said valve, said head being constructed and arranged for operation, by movement of the liquid in the font, to open the valve, and means for normally closing the latter.

3. A fountain brush comprising a font, a brush element, a valve between said parts, a head positioned within the font and having peripheral recesses forming passages for the liquid, said head being operable by inertia inaugurated by shaking the brush to open the valve, and means for normally closing said valve.

4. A fountain brush comprising a font, a brush element, and a cap for said brush element, said font having a depression adapted to receive the closed end of said cap.

In testimony whereof I affix my signature in the presence of these two witnesses.

HARRY SEMPLE.
